UNITED STATES PATENT OFFICE.

HARVEY GAGNÉ, OF ST. JEAN D'IBERVILLE, QUEBEC, CANADA.

RAILWAY-SWITCH.

Specification of Letters Patent. Patented Dec. 28, 1920.

1,364,046.

Application filed September 1, 1920. Serial No. 407,298.

To all whom it may concern:

Be it known that I, HARVEY GAGNÉ, a subject of the King of Great Britain, residing at St. Jean d'Iberville, Province of Quebec, Canada, have invented certain new and useful Improvements in Railway-Switches; and I do hereby declare that the following is a full, clear, and exact description of the invention, such as will enable others skilled in the art to which it appertains to make and use the same.

The present invention relates to new and useful improvements in railway switches.

A primary object of the invention is the provision of a switch throwing apparatus which will hold the switch points in either open or closed position against any undesired displacement.

A further object of the invention is the provision of a device of the above specified type which will operate to throw the switch points and hold them in their opposite positions, and which will also operate means for additionally locking the points in their said positions.

A further object of the invention is the provision of spring locking means for holding the switch points in closed position which are actuated upon the throwing of the said switch points in the usual manner.

A still further object of the invention is the provision of a railway switch for the purposes above specified, which will be comparatively simple and inexpensive to manufacture, reliable and efficient in use, and readily operated.

With the above and other objects in view, the present invention resides in the novel features of construction, formations, combinations and arrangements of parts to be hereinafter more fully described, claimed, and illustrated in the accompanying drawings forming a part of the present application, and in which:

Figure 1 is a plan view of a portion of the switch constructed in accordance with my invention;

Fig. 2 is a transverse sectional view showing the actuating means in side elevation;

Fig. 3 is an enlarged sectional view of the left hand track section shown in Fig. 2;

Fig. 4 is a similar view of the right hand track section;

Fig. 5 is a transverse sectional view taken on the line 5-5 of Fig. 4;

Fig. 6 is a vertical sectional view taken through the operating lever and pedestal;

Fig. 7 is a horizontal sectional view taken on the line 7-7 of Fig. 6; and,

Fig. 8 is an inverted detail perspective view of the lever locking device.

Referring now to the accompanying drawings by corresponding characters of reference throughout the several views, the numerals 1 designate a pair of railway rails mounted upon the ties 2 which are extended at one end thereof, as shown at 3, to support the switch operating mechanism. These extensions 3 are connected by the transverse bars 4 and 5 for a purpose to be later explained.

The ends of the switch points are shown at 6 and are of any usual construction. The inner sides of these switch points 6 have bolted or otherwise secured thereto inwardly extending plates 7 which are rigidly connected to each other by a plate 8 in order that both of said points 6 will be moved in unison.

An operating bar 9 is secured to one end of the plate 8 and is connected at its opposite end to an operating arm 10 secured rigidly to the lower end of a rotatable standard 11 mounted in the pedestal 12 and actuated through the medium of the lever 13, as shown by the full and dotted line positions in Fig. 1, to move the switch points in the desired manner.

The standard 11 has its upper end squared in cross-section, as shown at 14, in order to provide a means for locking the same against any undesired rotation.

A collar 15 is slidably mounted upon the squared portion 14 of the standard 11 and is provided with a lower squared extension 16 which fits in a corresponding socket 17 provided in the upper end of the pedestal 12. The lever 13 has its inner end bifurcated, as at 18, and pivoted to the brackets 19, which are in turn pivotally connected to the upper end of the collar 15, as shown at 20. The free terminals of the lever 13 are connected by a pin 21 which is rotatably mounted on a bracket 22 secured to one side of the squared portion 14 of the standard 11. This provides a hinge connection between the said standard and lever.

When it is desired to release the standard 11, the lever 13 is moved from the full line position shown in Fig. 6, to the dotted line

position, which raises the squared extension 16 of the collar 15 out of the socket 17, as is also shown by the dotted lines in this figure.

- 5 The lever 13 may then be rotated from the full line position in Fig. 1 to the dotted line position, which throws the switch points to their opposite position. The lever 13 may be then lowered and the extension 16 10 dropped again into the socket 17, which locks the points in this position.

Additional locking means is also provided for the rails, and is described in detail, as follows:

- 15 Straps 23 and 24 are hingedly connected, as at 25 and 26 to the plate 8, and are normally held in raised position parallel and flush with the said plates by the spring devices 27.
- 20 The strap 23 is bent upwardly at 28 to engage the base flange of the rail 1, as clearly shown in Fig. 3, thus locking the adjacent point 6 in closed position, while the strap 24 has a block or other suitable device 29 secured to its free end to engage the opposite side of the adjacent rail, thus locking the adjacent point, as shown in the dotted line position in Fig. 4.

A bar 30 is slidably mounted in guides 31 transversely of the track, and has attached at one end, in a suitable clevis 32, a chain 33 which passes over roller 34 and upwardly to the upper end of the pedestal where it is secured to an arm 34' carried by the squared portion of the standard 11 and movable upwardly therewith.

- Additional chains 35 are secured in suitable adjustable detaching devices 36 carried by the bar 30 and have their opposite ends 40 connected to the free terminals of the straps 23 and 24, as shown at 37.

Suitable rollers 38 may be provided to guide said chains and insure their proper movement.

- 45 Obviously, when the collar 15 is raised through the instrumentality of the lever 13, the switch points 6 will first be released, and then, upon movement of the lever, as shown by the dotted lines in Fig. 1, the said switch points will be thrown to open or closed position, as is desired. Upon the depression of the lever 13 to retain the parts in their adjusted positions, the spring devices 27 will force the straps 23 and 24 upwardly again, 50 locking said switch points against any undesired displacement.

From the foregoing description, taken in connection with the accompanying drawings, it will be manifest that a railway 60 switch and operative means therefor are provided, which will fulfil all of the necessary requirements of such a device, and it should be understood in this connection that various minor changes in the specific details 65 of construction can be resorted to within the

scope of the appended claims, without departing from the spirit or sacrificing any of the advantages of the invention.

Having thus fully described my invention, what I claim as new and desire to protect by Letters Patent is:—

1. In a device of the character described, the combination with a pair of rails and switch points, of a vertically movable and rotatable actuating device for the switch points, means connected to the actuating device for throwing the switch points upon its rotation, and means carried by the actuating device for locking and releasing said rails upon the vertical movement thereof. 80

2. The combination in a device of the character described, with a pair of switch points and a pair of rails, a plate connecting the said switch points, a vertically movable and rotatable actuating device connected at one end to the plate, and means connected to this said device for locking and releasing the switch points upon vertical movement of the actuating device. 85

3. In a device of the character described, the combination with a pair of rails and switch points, a plate connecting said switch points, a transversely movable actuating bar, locking means for the switch points connected to said bar, an actuating device 95 for the switch points, a locking means for said device, and means connecting the locking means and actuating bar for locking and releasing the switch points upon proper movement of the actuating device. 100

4. In a device of the character described, the combination with the rails of a railway track and a pair of switch points co-operating therewith, a plate connecting said switch points, a pedestal, a standard rotatable therein, an arm carried by the standard, means connecting said arm to the plate for actuating the switch points upon the rotation of the standard, a collar rotatable with the standard, a locking engagement between the collar and the pedestal for holding the standard against rotation, and means carried by the pedestal and engaging the standard for releasing the same. 110

5. In a device of the character described, the combination with a pair of rails and switch points, a connection between the same, a pedestal, a standard rotatable therein, an operative connection between the standard and plate for actuating the switch points upon rotation of the standard, the upper end of said standard being squared and a squared socket provided in the pedestal, a collar slidable upon the squared end of the standard, a squared extension formed 125 upon the collar and engaging the socket in the pedestal for locking the standard against rotation, a lever hinged to the standard, and means connecting the lever and collar for raising and lowering the latter and locking 130

and unlocking the standard against rotation.

6. In a device of the character described, the combination with a pair of rails and switch points, a pedestal, a standard rotatable therein and pivotally connected to the switch points for actuating the same, locking means for said rails, a vertically movable collar for locking the standard against rotation, and an operative connection between the said collar and rail locking means for locking and releasing the latter.

7. The combination in a device such as described, with a pair of switch points and rails with which said switch points coöperate, means for operating the switch points including a rotatable standard, a locking collar for the same, a connection between the standard and switch points, straps hinged adjacent the switch points and engaging the rails for locking the switch points in engagement, and an operative connection between the straps and the locking collar for the standard for actuating the straps.

8. In a device of the character described, the combination with a pair of rails and coöperating switch points, a plate connecting the switch points, straps hinged to the switch points for engagement with the rails

for locking the switch points against displacement, means for holding the straps in their locking positions, a rotatable standard, an operative connection between the standard and plates for actuating the switch points, a sliding locking collar on said standard for locking the latter against movement, and an operative connection between the collar and straps for locking the switch points in engagement with the rails. 40

9. In a device of the character described, the combination with a pair of rails and a pair of coöperating switch points, a rotatable standard, an operative connection between the standard and switch points for actuating the latter, a slideable collar upon the standard for locking the same against rotation, an actuating bar positioned beneath the rails, straps locking the switch points in engagement with the rails, a flexible connection between each of said straps and actuating bar, and a flexible connection between the actuating bar and collar whereby upon movement of the collar to release the standard, the straps will be moved out of engagement with the switch points and the latter released.

In witness whereof I have hereunto set my hand.

HARVEY GAGNÉ.
